UNITED STATES PATENT OFFICE.

BERNHARD KRÄMER, OF CHARLOTTENBURG, GERMANY, ASSIGNEE TO GENERAL ELECTRIC COMPANY, A CORPORATION OF NEW YORK.

PUMP MECHANISM FOR INTERNAL-COMBUSTION ENGINES.

1,158,062.

Specification of Letters Patent. Patented Oct. 26, 1915.

Application filed February 10, 1913. Serial No. 747,402.

To all whom it may concern:

Be it known that I, BERNHARD KRÄMER, a subject of the Emperor of Germany, residing at Charlottenburg, Germany, have invented certain new and useful Improvements in Pump Mechanism for Internal-Combustion Engines, of which the following is a specification.

At the present time there are engines operating on the constant or substantially constant pressure plan in which two kinds of fuel are used, a heavy and a light. These fuels may be used simultaneously, or the light fuel may be used until the engine is well heated after which its use is discontinued and the heavy fuel used exclusively.

My invention relates to a pump mechanism for supplying light and heavy fuels to an internal combustion engine, and has for its object to provide a pump mechanism of improved construction, whereby either or both of said fuels may be delivered to the engine at will under the control of a suitable governor.

For a consideration of what I believe to be novel and my invention, attention is directed to the accompanying description and claims appended thereto.

In the accompanying drawings which are illustrative of my invention, Figure 1 is a longitudinal section through my improved pump and governing mechanism therefor; Fig. 2 is a view partially in elevation and partially in section of the same, the said section being taken on line 2—2 of Fig. 1; Fig. 3 is a detail view in front elevation of one of the pumps; Fig. 4 is a view partially in elevation and partially in section of the means for actuating one of the suction valves; Fig. 5 is a development of a cam for actuating a suction valve; Fig. 6 is a section of the cam taken on line 6—6 of Fig. 5; Fig. 7 is a detail view showing the emergency governing mechanism; Fig. 8 is a detail view of a part of the structure of Fig. 7 taken at right angles thereto; Fig. 9 is a detail view of a cross-head and means for positively moving it; Fig. 10 is a detail view of the means for holding the plunger and valve actuating rollers in place, and Fig. 11 is a view illustrating the arrangement of the fluid passages leading to a suction valve.

10 indicates the shaft for actuating the

pumps and is supported by bearings 11 and 12 at its ends. This shaft may with advantage be utilized to operate the valves admitting fuel to the engine and also the air starting valves when such latter valves are employed. It is driven by the main shaft in any suitable manner. The shaft is inclosed in a divided housing 13 of any suitable construction, the top part of which is removable and is secured in place by suitable means. Keyed or otherwise secured to the shaft 10 is a bevel gear 14 that meshes with a similar gear 15 carried by the vertically disposed governor shaft 16. Formed integral with the gear 15 is a second gear 17 for driving the shaft 18, Fig. 2, which in turn is provided with a bevel gear 19 that meshes with a similar gear on the shaft of the tachometer 20.

The governor shaft 16, Fig. 1, is mounted in a suitable bearing and on its upper end is provided with a horizontal head 21, upon which are pivotally supported the governor weights 22. The outward movements of the weights are opposed by a coiled compression spring 23 having a fixed abutment 24. The lower end of the spring engages a movable abutment 25, said abutment being guided by a tubular member 26 that is supported by the head 21. The movable abutment is connected to the governor lever 27, Fig. 2, through a suitable slip-joint in the ordinary manner. To the outer end of the governor lever is attached a rod 28 containing a device for adjusting its length, such for example as the turn buckle 29. The lower end of the rod is connected to a bell-crank lever 30, shown in dotted lines Fig. 1. This crank is rigidly attached to the spindle 31, the latter being provided with suitable bearings in the pump casing. To the downwardly extending arm of the crank 30 is attached a rod 32, shown in dotted lines which is connected to the spindle 34. The object of this arrangement is to synchronize the movement of the devices for controlling the suction valves of the two parts of the pump, as will appear more fully hereinafter.

Two pump casings 35 and 36 are provided. The former serving as a pump for heavy oil and the latter as a pump for light oil. Instead of utilizing the pumps for different kinds of fuel they may be utilized for simi-

lar fuels. As will appear later, one or both of the pumps may be used. Viewed from this point, one pump may supply the fuel under normal conditions and the other be used as a spare. The greatest utility of the invention is obtained, however, when two kinds of fuel are employed. The pump casings are provided with downwardly extending front and rear portions 35^a, Fig. 2, supported by the lower half of the housing of the driving shaft 10. Between the pump casings and forming a partial support therefor is a housing 37, Fig. 1, that incloses the parts of the speed governor.

The construction of each of the pumps is similar so that a description of one of them will be sufficient. The pump casing is provided with four longitudinal and vertically extending cylindrical openings to receive the pump plungers, and also the suction valves, and their lifters or actuators. As will be seen the cylindrical openings or bores to receive the pump plunger and suction valve lifters are of the same diameter. This is advantageous because the same tools can be used for drilling and finishing.

40 and 41 indicate the pump plungers, each of which is snugly fitted within a sleeve 42, the latter being flanged at the top 30 and resting on a shoulder formed in the pump casing. The pump plungers are made hollow to reduce weight and are closed at their upper ends. The lower end of each plunger is provided with a head 43 upon 35 which is seated coiled compression spring 44 that serves at all times to force the plunger downward. Located in each tubular plunger is a plug 45 that engages a projection on the reciprocating cross-head 46. This cross-head is made cylindrical and is snugly fitted into a counter-bore in the casing, said bore being alined with the plunger. The underside of each cross-head has two small recesses to receive the spindle 47 40 of the anti-friction roller 48. This roller is arranged to engage the peripheral surface of the cam 49, the latter being keyed to and driven by the shaft 10. As shown, the left hand plunger is at the lower end of its suction stroke and the right hand plunger 41 at the end of its discharge stroke.

The pump plunger 40 co-operates with a suction valve 50 and the plunger 41 with a suction valve 51. These valves are similar 55 in construction and have similar means for controlling their action. Each suction valve is normally held against its seat by a light compression spring 52, the seat for which is in the upper end of a perforated sleeve 53 60 that is snugly fitted into the pump casing and is provided with a flange on its upper end engaging a shoulder in the pump casing. Located within the sleeve is a tubular lifter or actuator 54 having a flange on its 65 lower end, and between the flange and a

part of the casing is a coiled compression spring 55 that tends at all times to force the actuator 54 away from the suction valve and permit the same to close. Like the pump plunger the suction valve actuator is moved by a roller 56 which is carried by a sliding cross-head similar to the cross-head 46 previously described. It is however, somewhat smaller in diameter and has rounded edges to facilitate its travel on the co-operating cam. As before stated the pump casings are removable and to prevent the rollers 48 and 56 from dropping out when the casing is removed, retaining devices 57 are provided in the form of thin flat plates through which the rollers project, the retaining devices for each roller being separate from the others. These plates are shown in bottom plan view in Fig. 10, and one of the cross-heads in Fig. 9.

As shown, the pump plungers are located at the sides of the casing and the suction valves and their actuating devices in the central portion of said casing, the object of this is to simplify the arrangement of the cams for operating the suction valve lifters and the pump plungers.

Each pump casing is provided with a chamber 57^a to which fuel is admitted from a tank or other suitable source by the pipe 57^b. From this chamber fuel flows through one or more openings 57^c, Fig. 4, to an annular passage or chamber surrounding the perforated sleeve 53, and from this chamber it flows through perforations in the sleeve 100 to the suction valve, as will appear more fully in connection with Fig. 11. Since there is liable to be a small amount of leakage around the pump plungers and also around the valve lifters, and since it is important to know how much, if any, leakage exists, a horizontal passage 57^d, Fig. 1, is provided that communicates with perforations in the sleeves surrounding the pump plungers and valve lifters. This passage 110 communicates with a passage 57^e extending perpendicular thereto, the latter terminating at the point of the valve casing as shown in Fig. 3. This passage is also shown in Fig. 7 together with the boss on the front of the casing, which boss is provided with a thin front edge or drip lip 57^f.

Referring now to the cam mechanism for controlling the suction valves, 58 indicates a sleeve which is rotated by the shaft 10, but is capable of axial movement thereon. This is effected by the spline or feather 59, which is seated in the shaft 10. Mounted on the periphery of the sleeve are two cams 60 and 61. Said cams being held on the sleeve between a shoulder and a screw threaded nut. Between the cams is a loose ring 62 for shifting the cams axially. The shape of each of these cams is best illustrated in Figs. 5 and 6, in which 63 represents the high portion 130

of the cam and 64 the low portion. The two portions of the cam are connected by a bevel surface 65, so that the roller 56, which has a rounded peripheral surface, can readily pass from the low to the high portions and vice-versa. It will be noted that the high portion of the cam is wider at one end than at the other, so that by moving the cam in an axial direction the period that the suction valve will be held off of its seat for each rotation of the cam can be varied. That is to say, when the cam is so positioned that the roller 56 engages it near the right hand side it will be held open for a much greater period than when it is near the left hand side. In other words, when the roller is riding on the raised portion 63 of the cam the suction valve is held open and when riding on the low portion 64 of the cam the suction valve is permitted to close. In order to adjust the cams axially on the shaft two arms 66 are provided that are connected to the loose ring 62. One of these arms is shown in dotted lines, Fig. 1, and both are shown in full lines in Fig. 2. These arms are rigidly mounted on the horizontal spindle 31, so that as the governor moves the connecting rod 28 and its attached arm 30, the cam will be moved in one direction or the other dependent on the change in speed of the engine.

In an arrangement of this kind it is desirable to synchronize the movement of all the suction valves so that they will have the same period of opening and closing for the same speed. To this end a pair of arms 67 are provided resembling the arms 66. These are mounted on the spindle 34, Fig. 1, so that as the rod 32, shown in dotted lines, moves back and forth the cams 60, 61, 68 and 69 will be correspondingly moved and by like amounts. These cams are normally urged to the right by coiled compression springs 70 and 71, that are located between the pump cams and the sleeves carrying the valve cams.

In a mechanism of this character it is highly desirable to provide a means for filling the pump chambers prior to starting the engine, so as to insure proper delivery of fuel to the pulverizers, atomizers or injectors in the engine cylinders. To this end I provide a hand actuated pump for each pump, comprising a plunger 73 that may be depressed by the handle 74 against the action of a coiled compression spring 75. On the end of the plunger is a head 76 that also serves as a valve to prevent the escape of high pressure oil when the hand pump is not in operation. By depressing the plunger 73 a few times prior to starting, oil will be forced into the pump chamber and connected parts to fill the same, thereby insuring good working of the power pumps.

Each pump is provided with a discharge

valve 77, Fig. 2, which is normally held against its seat by a coiled compression spring 78. Fuel from the pump enters the discharge valve chamber by the passage 79 formed in the casing. To the discharge side 70 of the valve is connected a pipe 80 leading to the fuel injector in the engine cylinder.

In an engine of this character it is sometimes necessary to shut it down very quickly, as in the case of accidents, and the quickest way to accomplish this is to cut off the supply of fuel to the cylinders. To this end I provide an unloading or by-pass valve 81, Figs. 2 and 7, which is normally held in the closed position by the coiled compression spring 82, the latter engaging a collar 83 on the valve stem at one end and a fixed abutment at the other made in the form of the tubular member 84. The member 84 is capable of a limited longitudinal movement in 80 the pump casing sufficient to relieve the spring tension. It is normally held against outward movement by the latch 85 which engages an annular shoulder formed on the periphery thereof. When the latch 85 releases the tubular member 84, the latter moves to the right, due to the pressure of the spring 82 and to the fuel pressure issuing from the passage 79 on its way to the discharge pipe 80. Under these conditions 95 the valve 81 will be held open and all the fuel from the passage 79 will be by-passed to the chamber 86, from which it is conveyed through the passage 87 to the drip 88 on the front of the casing. In order to reset 100 the tubular member a handle 89 is provided by means of which the tubular member can be moved far enough to the left to permit the latch 85 to engage the shoulder. This arrangement also forms a safety device, in 105 that the spring 82 is so designed as to hold the valve closed for any pressure up to the maximum, and thereafter to yield and permit a certain amount of the fuel to be by-passed from the passage 79 to the chamber 110 86 instead of passing through the pipe 80 to the engine.

The latch 85 is controlled by an emergency governor comprising a ring 90, Figs. 1 and 7, that is mounted in a holder 91, which is 115 keyed to the shaft 10. This ring has a greater mass on one side of its axis than the other, and is normally held in the position shown by the coiled compression spring 92. When, however, the speed exceeds a 120 certain predetermined maximum the ring moves in a plane transverse to the shaft and engages a trigger 93 which actuates the latch 85.

The latch 93 has a pivot 94 on which it 125 is adapted to move, also a projection 95 arranged to strike the stop 96. Resting on a shoulder on the latch is a vertical rod 97 that is normally depressed by the coiled compression spring 98. On the upper end 130

of the rod is a forked head 99 that embraces an arm 100 fastened to one end of the latch 85. When the rod is raised by the trigger the latch 85 is slightly oscillated and the abutment 84 released, permitting the valve 81 to open.

It is sometimes necessary or desirable to cut all of the pumps out of service in starting or to cut one pump plunger out of service without disturbing the others. An arrangement for this purpose is shown in Figs. 4 and 9 wherein 101 indicates a spindle having a crank 102 on its inner end and a squared outer end to receive a socket wrench. The crank enters a notch 103 cut in the side of the cross-head which communicates motion to a suction valve. When the crank is in the position shown the cross-head is free to move up and down under the action of the cam on the shaft 10 but when turned through 180 degrees the cross-head is raised above the path of the cam and the suction valve is held open. This means that the pump plunger can move back and forth, drawing in a charge of fuel through the suction valve and discharging it again through the same. In Fig. 9 is also shown one of the slots 104 to receive the pivot of an anti-friction roller. On the left side of the cross-head is a feather 105 engaging the casing to prevent the head from turning but permitting it to move up and down. As before stated, the cross-heads of the pump plungers and valve lifters are similar in construction but the cross-heads of the former are slightly larger than the latter.

Referring to Fig. 11, 35 indicates the casing which has a cylindrical bore or opening to receive the perforated sleeve 53. Between the sleeve and the wall of the cylinder is an annular chamber or passage 106 that receives fuel from the pump chamber by one or more openings 57^c. From the chamber it passes through one or more openings 107 to the region around the suction valve. 57^d indicates the leakage receiving passage which registers with openings 108 in the sleeve to receive any fluid leaking around the valve lifter 54.

In starting the engine by air under pressure or other means the suction valves are raised and held from seating by the spindles 101 to avoid pumping excess charges of oil into the cylinders. When the engine is up to speed and the charges of air in the cylinder are properly heated the suction valves are put into operation and the starting means cut out of operation. The rotation of the shaft 10 moves the pump plungers and valves in their proper sequence and the portion of the plunger strokes that the suction valves are held open will be determined by the cams 60, 61 and 68, 69 which are movable axially on the shaft in response to the speed governor. The greater the portion of

the stroke the valves are positively held open the less will be the amount of fuel delivered by the pipes 80 to the engine cylinders.

My apparatus is especially adapted for pumping fuels under high pressures and at high speeds. It has the advantage of being exceedingly rugged and compact, and taking into account the character of the work to be performed is simple in construction and not liable to get out of order. By taking off a casing the entire mechanism of the pump can readily be exposed. By taking out the plugs over the suction valves the latter can be removed and examined without disturbing any of the other parts. By arranging the plungers and valve actuators in parallel cylindrical bores in the same casing the alinement will always be preserved.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:

1. In a pump, the combination of a driving shaft, pump casings extending perpendicularly to the shaft and separated by a space, a spaced governor located in the space between the casings and driven by the shaft, plungers in the casings that are moved by the shaft, suction and discharge valves cooperating with the plungers, adjustable cams on the shaft for moving the suction valves, means connecting the cams for simultaneous movement, and a device operated by the governor for moving the cams axially on the shaft.

2. In a pump, the combination of a driving shaft, a housing therefor, pump casings extending perpendicularly to the shaft and supported by the shaft housing, a speed governor located between the pump casings, a housing for the governor supported by the shaft housing, plungers for the casings, suction and discharge valves for the plungers, a set of cams fixed on the shaft for moving the plungers, a second set of cams mounted on the shaft and adjustable axially thereon to regulate the period of closing of the suction valves, and a connection between the speed governor and the second set of cams to move them axially on the shaft.

3. In a pump, the combination of a driving shaft, a pair of casings spaced from each other and each containing a plurality of parallel cylindrical bores, suction and discharge valves, plungers located in certain of said bores, suction valve actuators located in the remaining bores, anti-friction rollers co-operating with the plungers and actuators, 12

- 5 cams driven by the shaft and engaging the rollers, and means located in the space between said casings for moving the cams that actuate the suction valves to control their period of closing.
4. In a pump, the combination of a driving shaft, a casing containing a plurality of cylindrical bores, suction and discharge valves, plungers located in the outside bores, suction valve actuators located in the adjacent inside bores, cams for moving the actuators, a holder slidably mounted on and rotated by the shaft which carries said cams, other cams fixed on the shaft and located at the ends of said holder, and means for moving the holder on the shaft.
5. In a pump, the combination of a driving shaft, a casing containing a plurality of cylindrical and parallel bores, suction and discharge valves, plungers located in some of the bores, suction valve actuators located in the other bores, a chamber that supplies liquid to the suction valves, a passage that communicates with the bores of the plungers to receive leakage, means driven by the shaft for moving the plungers and actuators, and means for varying the effective action of the actuators on the suction valves.
6. In a pump, the combination of a casing having a cylindrical bore and counter-bore, a hollow member located in said bore which is closed at its ends, a cylindrical cross-head for the member which is located in the counter-bore and engages the member, a roller for moving the cross-head, a compression spring that tends to move the member out of the casing, and means engaging the roller to move the member against the action of the spring.
7. In a pump, the combination of a casing containing a cylinder, a plunger therein, suction and discharge valves coöperating with the plunger, a lifter for one of the valves, cam means for reciprocating the plunger and moving the lifter, means for controlling the period during which the cam means engages the lifter to regulate the valve, a device for moving the lifter to a position where it positively holds its valve open and is out of the path of said means, and a shaft for driving said cam means.
8. In a pump, the combination of a casing containing a cylinder, a plunger therein, suction and discharge valves coöperating with the plunger, a lifter for one of the valves, a driving shaft, a cam on the shaft for moving the plunger, a second cam also on the shaft for moving the lifter, means for moving the second cam on the shaft to vary the period of closing of one of the valves, and a means extending through the casing for moving the valve lifter out of the path of the second cam, and to a position to hold the suction valve open.
9. In a pump, the combination of a casing containing a cylinder, a plunger therein, suction and discharge valves coöperating with the plunger, a lifter for the suction valve, a spindle having a crank at one end which is adapted in one position to engage and raise the lifter to hold its valve open, cam means for operating the lifter and plunger and a shaft for driving said cam means.
10. In a pump, the combination of a casing containing a supply chamber and a plurality of bores, a plunger located in one of said bores, a suction valve located at one end of another of the bores, a perforated sleeve located in the last named bore and separated from the wall thereof for a portion of its length by a fluid carrying space, certain of said perforations communicating with the chamber, a passage for conveying leakage from the interior of the sleeve, and a lifter for the valve located in said sleeve.
11. In a pump, the combination of a cylinder, suction and discharge valves therefor, a plunger, a lifter for the suction valve, means for reciprocating the plunger and lifter in the normal operation of the pump, means for changing the phase relation of the plunger and lifter to vary the amount of fluid discharged from the cylinder, and means for moving the lifter out of the path of its normal actuating means, and into a position where it maintains the suction valve open.

In witness whereof, I have hereunto set my hand this 7th day of January, 1913.

BERNHARD KRÄMER.

Witnesses:

HARRY LEHMANN,
FRANZ BRANN.

It is hereby certified that in Letters Patent No. 1,158,062, granted October 26, 1915, upon the application of Bernhard Krämer, of Charlottenburg, Germany, for an improvement in "Pump Mechanism for Internal-Combustion Engines," an error appears in the printed specification requiring correction as follows: Page 4, line 98, claim 1, for the word "spaced" read *speed*; and that the said Letters Patent should be read with this correction therein that the same may conform to the record of the case in the Patent Office.

Signed and sealed this 23rd day of November, A. D., 1915.

[SEAL.]

J. T. NEWTON,

Acting Commissioner of Patents.
